HARRY E. NORVIEL, OF ANDERSON, INDIANA, ASSIGNOR TO GENERAL MOTORS CORPORATION, A CORPORATION OF DELAWARE.

ELECTRIC SWITCH.

Application filed November 1, 1923. Serial No. 672,180.

This invention relates to electrical switches and has among its objects to prevent the unauthorized completion of an electric circuit, such as the electrical ignition circuit for an automobile.

In order to attain this object the present invention consists of a plurality of electric switches connected in series and concealed within a switch case carrying a rotatably mounted disc covering openings in the switch case through which the switches may be operated by means of an operating handle or plunger carried by the disc. Therefore the combination cannot be detected as in the case where the individual switches have their operating members exposed, and the use of any particular switch can be detected by the amount of wear to which an exposed surface has been subjected. The invention provides also for making it difficult to detect the status of any of the switches, that is, whether it is open or closed. The invention provides for making it difficult to detect the combination by repeated trials, since the switch combination can be set up only by turning the disc in one direction. Turning the disc backward causes the combination to be upset even though the combination has been partially completed. The backward movement of the disc is used as a means for opening the circuit completed by the combination switch and for upsetting the combination, thereby, providing a lock for the switch.

Further objects and advantages of the present invention will be apparent from the following description, reference being had to the accompanying drawings, wherein a preferred form of embodiment of the present invention is clearly shown.

In the drawings:

Fig. 1 is a front elevation or face view of a form of switch including the present invention.

Fig. 2 is a longitudinal sectional view taken on the line 2—2 of Fig. 1.

Fig. 3 is a transverse sectional view taken on the line 3—3 of Fig. 2.

Figs. 4 and 5 are sectional views on the line 4—4 of Fig. 3 showing two of the switches of the combination switch in different positions.

Figs. 6 and 7 are sectional views of switch

operating mechanism in two positions corresponding with the positions of the switches shown in Figs. 4 and 5, respectively.

In the drawings 20 designates a switch case provided with a plurality of apertured bosses 21 and a central opening in the front face 22 thereof for receiving a shaft 23 attached to a movable carrier or face plate 24. Face plate 24 is provided with a knurled edge 25 to facilitate turning the plate and with a switch actuator or plunger 26 located in alignment with the apertured bosses 21 which are arranged in a circular row concentric to the shaft 23. The plunger 26 is returned by a spring 27 to the position shown in Fig. 2. Face plate 24 is provided with a plurality of depressions 28 one for each position of the disc. A spring pressed ball 29, pressed outwardly by the spring 30 located within a recess in the wall 22 of case 20, cooperates with the depressions 28 to assist in locating the plate 24 in its different positions.

The switch case 20 is provided with a detachable cover or back plate 31 secured by screws 32. The plate 31 carries a stud 33 having a head 34. The stud is apertured to receive a reduced portion 35 of the shaft 23 which is threaded at its outer end to receive nuts 36 and 37. Between the plate 31 and nut 37 there is located a plain washer 38 and a spring washer 39. A spring 40 normally tends to press a contact supporting disc 41 against a ratchet member 42 having ratchet teeth 43, and said ratchet member 43 is in turn pressed against the head 34 of stud 33. Ratchet member 42 carries a pin 44 which cooperates with a plurality of camming members 45 with which the cam 46 of the disc 41 is provided. The teeth 43 of ratchet 42 cooperate with the teeth 47 of ratchet 48 which is connected with the shaft 23 for rotation therewith as well as for endwise movement relative thereto. This connection is provided by means of a pin 49 carried by the shaft 23 which projects into a slot 50 carried by the ratchet 48. A spring 51 tends normally to hold the ratchet members 48 and 42 in engagement.

Each individual switch of the combination switch includes a pair of contacts 60 and 61, the contact of one pair being connected with the adjacent contact of another pair by

means of a strap 62 which is preferably integral with the contacts which it connects, with the exception of a contact 60^a which is connected with a terminal 63 and a contact 61^a which is connected with a terminal 64. These terminals extend through holes 65 provided in the switch back 31 and receive nuts 66 for securing a wire thereto. Obviously if all of the pairs of contacts 60, 61 are bridged by an electrical conductor, an electrical circuit will be completed between the terminals 63 and 64.

Each individual switch includes also a movable operating member or push rod 67 of non-conducting material having between its ends grooved surfaces 68 and 69. The surface 68 is non-conducting and the surface 69 is conducting and is provided by a conducting band 70 shown in section in Fig. 3. Each rod 67 is slidable within an apertured boss 21 and the rods are located some with the conducting band 70 located nearest the boss 21 and some with the non-conducting groove 68 nearest the boss 21. Each end of the rod 67 is provided with a central bore 71 adapted to receive the shank 72 of a plunger having a head 73 slidable in the boss 21. A spring 74 tends to maintain the head 73 in engagement with the disc 24 or with the inner end of plunger 26 as shown in Fig. 4.

The switch case 20 is provided with lugs 80 received by notches 81 provided in the plate 41 in order to prevent rotation of said plate.

The mode of operation of the invention is as follows:

After a combination has been upset in a manner to be described, all of the push rods 67 will be located as shown in Fig. 2. Some of the rods may be in contact making position, and others not, therefore only those rods which are not in contact making position should be operated. The switch which is illustrated on the drawings shows eight rods 67 which for convenient reference may be numbered from 1 to 8 beginning with the rod at the top of the drawings as No. 1 and proceeding in a clockwise direction. Therefore there are eight positions of the face plate 24 and plunger 26, and these positions are indexed by the spring pressed ball 29 which will move into one of the depressions 28. Referring to Fig. 3 it is apparent that push rods 67 which are in positions 2, 3, 4, 6 and 8 are so located that their conducting bands 70 are in contact making position, therefore, these particular push rods are not operated to set up the combination. To set up the combination the push rods located in positions 1, 5 and 7 should be pushed in. This can be done by turning the face plate 24 so that the plunger 26 is in position No. 1 as shown in Fig. 1. Pressing the plunger 26 will cause the plunger head

73 to move in against the end of the rod 67 causing the non-conducting portion 68 to move away from a pair of switch contacts 60 and 61 and the conducting portion 69 to move between said pair of contacts. When the plunger 26 is released, it will be returned by the spring 27 and the plunger head 73 will return by the spring 74 into engagement with the face plate 24. Then the plunger 26 is turned into positions 5 and 7 and operated in the same manner.

The plunger 26 therefore constitutes a common operating member for all of the switch plungers which are actuated for setting up the combination. The switch rods themselves are concealed so there is no way of telling by external appearance which of the individual switches have been subjected to frequent operation.

No matter what the status of a switch rod 67 is, that is, whether in or out of engagement with its switch contact this status cannot be readily detected because the member 73 which transmits motion from the plunger 26 to the rod 67 always returns to a position against the face plate 24, thereby providing a plug for the aperture in boss 21.

After a switch rod 67 has once been pushed in it cannot be restored except by counterclockwise rotation of the face plate 24 and such movement of the plate causes all of the rods 67 to return to the position shown in Fig. 2 thereby upsetting the combination. This result is accomplished by means of the ratchet mechanism shown in Figs. 6 and 7. When the face plate 24 is moved clockwise the ratchet 48 will turn in the direction of the arrow 82 shown in Fig. 6 and the teeth 47 of ratchet 48 will ride over the teeth 43 of ratchet 42 thereby compressing the spring 51 beyond its normal state of compression. Then the spring 51 will return the ratchet 48 to the position shown in Fig. 7. The spring 51 is relatively weaker than the spring 40, hence the ratchet 43 will not be moved endwise toward the right of the drawing to any substantial amount. Fig. 6 shows a position taken by the ratchet 48 as the plate 24 is moving into one of its operative positions, so that the plunger 26 can be operated as shown in Fig. 4. If the face plate 24 is turned counterclockwise so that the ratchet 48 will be moved in the direction of arrow 83 in Fig. 7, the teeth 47 of ratchet 48 will grip the teeth 43 of ratchet 42 and cause ratchet 42 to move in the same direction. The pin 44 will be moved from a position such as shown in Fig. 6 into a position such as shown in Fig. 7. Thus the pin 44 cooperates with the camming members 45 to move the contact support 41 into the position shown in Figs. 5 and 7. When the contact plate 41 is thus moved, the pairs of contacts 60 and 61 will each engage that grooved portion of

115
120
125
130

a rod 67 which is nearest to the back of the switch. When the face plate 24 is turned still further, the pin 44 will clear one of the camming members 45 permitting the spring 40 to move the plate 41 into its normal position and all of the contact rods 67 will be located as shown in Fig. 2 and the switch combination will be upset and the circuit between the terminals 63 and 64 will be interrupted.

The present invention can be used advantageously to turn on or complete the ignition circuit of an automobile. Instead of using a key to permit the operation of a switch lever, a certain combination of switches is operated. The ignition circuit is broken to stop the engine by rotating the face plate 24 counterclockwise which will result in upsetting the combination, and in locking the ignition circuit open or "off". In other words, stopping the engine causes the ignition circuit to be locked in inoperative condition, and there is no key to be removed from the lock.

If the automobile driver leaves the car with the engine running, an occupant cannot readily detect which switch rods have been pressed in to complete the ignition circuit because the plunger heads 73 are all the same distance from the plunger 26 regardless of the status of the switch rods 67.

In order to make it difficult to bridge the switch terminals 63 and 64, they may be enclosed in metal conduits 90 which receive the wires connected with the switch.

While the preferred form of embodiment of the present invention as herein disclosed, constitutes a preferred form, it is to be understood that other forms might be adopted, all coming within the scope of the claims which follow.

What is claimed is as follows:

1. A combination electric switch comprising, in combination, a plurality of switches connected in series, some of which may be normally closed and others normally open according to the combination desired, a switch actuating member, a movable carrier supporting the actuating member and adapted to locate the actuating member so that the normally open switches can be closed thereby, and means for restoring the switches to normal condition to upset the combination.

2. A combination electric switch comprising, in combination, a plurality of switches connected in series, some of which may be normally closed and others normally open according to the combination desired, a switch actuating member, a movable carrier supporting the actuating member and rotatable in one direction to locate the actuating member so that the normally open switches can be closed thereby, and means actuated by rotation of the movable carrier in the

other direction for restoring the switches to normal condition to upset the combination.

3. A combination electric switch comprising, in combination, a plurality of switches connected in series, each having a movable member, some of said switch members being normally in circuit closed position and others in circuit open position according to the combination desired, a switch housing enclosing said switches and provided with openings through which said switch members are actuated, an actuator adapted to operate said switch members through said openings, and a carrier supporting the actuator and covering said openings and movable to locate the actuator opposite any of said openings.

4. A combination electric switch comprising, in combination, a plurality of switches connected in series, each having a movable member, some of said switch members being normally in circuit closed position and others in circuit open position according to the combination desired, a switch housing enclosing said switches and provided with openings through which said switch members are actuated, an actuator adapted to operate said switch members through said openings, a carrier supporting the actuator and covering said openings and movable to locate the actuator opposite any of said openings, and devices each engageable by the actuator, when operating a movable switch member all of the devices having normally the same relation to the carrier when the actuator is released regardless of the status of the movable switch members.

5. An electric switch comprising, in combination, a switch case; a non-conducting push rod; a contact on said push rod; a contact member yieldingly engaging the push rod or its contact, dependent upon the position of the push rod; means for moving the push rod in one direction relative to the contact member yieldingly engaging said rod; means for moving the said contact member in the same direction and relative to the push rod to restore the normal relation of the contacts; and means for moving the contact member and the push rod simultaneously in the opposite direction to restore them both to normal location relative to the switch case.

6. An electric switch comprising, in combination, a switch case; a non-conducting push rod including encircling grooves; a grooved conducting band in one of said grooves; a yieldable contact member so constructed and arranged as to yieldably rest in either the push-rod groove or its grooved conducting band; means for moving the push rod in one direction relative to the yieldable contact to alter the relative position between the said contact and conducting

band; means for moving the yieldable contact in the same direction and relative to the push rod to restore the said yieldable contact and conducting band to original relative positions; and means for moving the contact member and the push rod simultaneously in the opposite direction to restore them both to normal location relative to the switch case.

7. A combination electric switch comprising, combination, a switch case; a plurality of non-conducting push rods; a contact on each of said push rods; a yieldable contact member for each push rod, said contact member normally engaging the push rod or the contact thereon, dependent upon the combination desired; means for selectively moving in one direction any of the push rods out of their normal yieldable contact-engaging positions; means for moving the yieldable contact members in the same direction relative to the push rods previously operated, to restore the normal relation of the contacts; and means for simultaneously moving all of the contact members and their respective push rods in the opposite direction to restore them all to normal location relative to the switch casing.

8. An electric combination switch comprising, in combination, a switch casing; a plurality of interconnected switches in said casing, said switches each including a non-conducting push rod having a conducting band; a pair of contact blades for each one of said interconnected switches, each of said blades yieldingly engaging its respective push rod or its conducting band when in normal position and dependent upon the combination desired; a face plate rotatably supported by the switch casing and provided with an actuating plunger adapted by rotation of the face plate, selectively to be brought into operative relation with any one of the push rods, said actuating plunger being operable in one direction to move the push rods out of normal position; means for simultaneously moving the switch blades in the same direction and relative to the push rods previously operated to restore the relative position of the blades and push-rod conducting band; and means for restoring all the switches in the casing to their normal positions relative to said casing.

9. A combination electric switch comprising, in combination, a switch casing; a plurality of switches in said casing, said switches including interconnected pairs of contacts mounted on a common insulated plate each yieldingly engaging a cooperating push rod; a face plate rotatably supported on the switch casing; means for selectively operating any of the push rods in one direc-

tion relative to its respective switch blades; a cam on the contact-blade supporting plate; a ratchet mechanism associated with the face plate and so constructed and arranged that when the face plate is rotated in one direction and into proper position the ratchet mechanism will cause the cam to be operated to move the contact-supporting blade in a direction similar to that in which the push rods have been previously operated whereby the contact blades will be moved relative to such respective push rods to restore the relative position between the push rods and blades; and means for returning the contact blades and push rods to their former position relative to the switch casing when the face plate is rotated in the same direction and into proper position.

10. A combination electric switch comprising, in combination, a switch housing including a plurality of apertured bosses; a plurality of switches in said housing, each switch including a pair of contacts and a push rod having a normal contact engagement and being supported in the respective apertured boss; a face plate rotatably supported on the switch housing and adapted to conceal the apertures of the various bosses; and an actuating member carried by the face plate and adapted to be brought into alignment with any of the said apertures in the bosses when the face plate is rotated, whereby the actuating member may be operated to move the respective push rods out of normal contact engagement.

11. A combination electric switch comprising, in combination, a switch housing including a circular-shaped, flat face and a plurality of inwardly-extending, apertured bosses; a plurality of switches in said casing, said switches including push rods slidably supported in the respective apertured bosses; a face plate rotatably supported adjacent the flat face of the switch housing and covering the apertures of the bosses; an actuating member carried by the face plate and adapted to be brought into proper alignment with the various apertures in the switch casing by rotation of the face plate; a yieldable stop to ensure registration of the actuating member and apertures; and a plunger in each aperture of the switch casing, having a spring interposed between said plunger and its respective push rod whereby said plunger is yieldingly held against the surface of the face plate to substantially prevent detection of operated push rods by the feel of the actuating member.

In testimony whereof I hereto affix my signature.

HARRY E. NORVIEL.
